UNITED STATES PATENT OFFICE.

JOHN T. BOYLE, OF MOUNT VERNON, ILLINOIS.

MAKE-AND-BREAK DEVICE FOR ELECTRIC CIRCUITS.

1,165,312.

Specification of Letters Patent.

Patented Dec. 21, 1915.

Application filed December 2, 1913. Serial No. 804,305.

To all whom it may concern:

Be it known that I, JOHN T. BOYLE, a citizen of the United States, residing at Mount Vernon, in the county of Jefferson and State of Illinois, have invented new and useful Improvements in Make-and-Break Devices for Electric Circuits, of which the following is a specification.

This invention relates to improvements in 10 make and break devices for electric circuits and has particular application to a device for making and breaking the circuit of an electric sign or like device whereby the lamps constituting such sign will be alternately 15 illuminated and extinguished.

In carrying out the present invention, it is 20 my purpose to provide a device of the class described which will be found especially useful in conjunction with signs embodying 25 a number of sets or banks of lamps or other ornaments and whereby the banks of lamps of the sign will be alternately illuminated and extinguished successively so that when one bank is illuminated the remaining bank 30 or banks as the case may be will be extinguished.

It is also my purpose to provide a make 35 and break device for electric circuits which will be entirely automatic in operation and 40 whereby the "flashing" of the lamps or other devices will be carried on for a predetermined time, and the circuit broken after such interval of time has passed.

With the above and other objects in view, 45 the invention consists in the construction, combination and arrangement of parts hereinafter set forth in and falling within the scope of the claims.

In the accompanying drawings, Figure 1 50 is a top plan view of a make and break device constructed in accordance with the present invention. Fig. 2 is a view in elevation of the same. Fig. 3 is a horizontal sectional view there-through, parts being shown in 55 elevation. Fig. 4 is a sectional view on the line 4—4 of Fig. 3. Fig. 5 is a similar view on the line 5—5 of Fig. 3. Fig. 6 is a fragmentary sectional view through the circuit interrupting device. Fig. 7 is a sectional view 60 through the operating mechanism for the main switch. Fig. 8 is a view in elevation of the latching device for the main switch. Fig. 9 is a plan view of the disk 65 of the circuit interrupting device. Fig.

10 is an end elevation thereof, parts being 55 broken away. Figs. 11 and 12 are bottom and top plan views respectively of the plate carrying the contacts and binding posts of the circuit interrupter. Fig. 13 is a dia- 60 grammatic view.

Referring now to the accompanying drawings in detail, A designates the supporting frame of the device, such frame comprising a base 1 composed of suitable insulating material and a plate 2 of insulating material 65 surmounting the base 1 and held above the same by means of posts 3 uprising from the base and connected to the plate. A vertical main shaft 4 is arranged approximately centrally of the supporting frame and journaled in alining bearings carried by the base 1 and the plate 2.

The interrupter for the electric circuit comprises a disk 5 of insulating material fast upon the upper end of the main shaft 70 4 and having embedded in the lower face thereof a metallic distributor comprising an annular conducting ring 6 arranged concentrically of the axis of the disk, and a segment 7 disposed concentrically of the ring 80 6 and electrically connected thereto. In the present instance, the ring 6 and segment 7 are formed integral with each other and the peripheral edge of the segment forms in effect a portion of the periphery of the disk. 85 Seated within recesses in the upper surface of the plate 2, as shown in Fig. 6 are socket members 8 spaced equal distances from the shaft 4 and from each other about such shaft and mounted within each socket member is 90 a shank 9 having the upper end thereof forked or bifurcated as at 10. Rotatably mounted within the forked end 10 of each shank 9 is a contact roller 11, while interposed between the lower wall of each socket member and the bottom of the shank thereof is a coiled expansion spring 12 acting to hold the contact rollers elevated and in frictional engagement with the under surface of the disk 5. These contact rollers, owing to 95 the positions of the sockets with respect to the axis of the disk, bear against the under face of the disk adjacent to the periphery thereof so that as the disk revolves the conducting segment 7 rides into and out of engagement 100 with the rollers successively. Formed in the upper surface of the plate 2 inwardly of the recesses carrying the socket members

105

8, as illustrated in Fig. 2 are recesses in which are seated socket members and within the socket members are disposed contact elements 16 similar in construction to those just described and shown in Fig. 6. The contact rollers of said elements engage the conducting ring 6.

Suitably fastened to the under surface of the plate 2 and depending therefrom is a 10 bus bar 19 shown in Figs. 2 and 11 electrically connected with the lower end of the contact elements 16 as at 17 in Fig. 11. Secured to the upper surface of the plate 2 are binding posts 20 corresponding in number 15 with the contact rollers and each disposed adjacent to one of the contact rollers and electrically connected therewith. This circuit interrupter is connected in series with the lighting circuit, the bus bar 19 being 20 connected with one side of the source of energy, while the binding posts 20 are connected with the various banks of lamps to be illuminated. By means of this construction, it will be seen that the contact elements 16 25 are continuously in engagement with the conducting ring 6, while the segment 7 engages and disengages the contact rollers 11 successively or one after the other, thereby making and breaking the circuit to the 30 banks of lamps as shown in Fig. 13. In order to prevent arcing when the rear end of the conducting segment 7 disengages the contact rollers, I pivotally connect to the rear end of the segment a metallic section 35 21 normally held at an angle to the segment by spring pressure and adapted to straighten out when engaged by a contact roller and subsequently leave such roller with a snap action thereby preventing sparking in the 40 breaking of the circuit. In the present instance, this metallic section has a rounded edge 22 set into a concavity 23 formed in the rear end of the conducting segment 7, as shown in Figs. 9 and 10, while a lug 24 45 is secured to the outer edge of the segment and formed with an aperture alining with a passage in the section 21 and an aperture in the adjacent portion of the conducting ring 6, a pivot pin 25 being passed through 50 the alining apertures and passages. Interposed between the upper surface of the lug 24 and the adjacent portion of the plate 2 is a leaf spring 26 acting upon the section 21 to hold the latter in normal position 55 and restore the same to such position with a snap action subsequent to the section leaving a contact roller.

Mounted upon the base 1 in proximity to the vertical main shaft 4 is an electric motor 27 geared up to the main shaft through the medium of a system of step down gearing 28 illustrated in Figs. 3 and 5. In the present instance, this gear system comprises a worm 29 fixed upon the motor shaft and meshing with a worm wheel 30

carried upon a horizontal shaft journaled in alining bearings 31 carried by the base 1. Surrounding the shaft of the wheel 30 and fixed to the latter is a worm 32 meshing with a self-oiling worm wheel 33 keyed upon the 70 shaft 4. By means of this construction, it will be seen that in the operation of the motor rotary motion will be transmitted to the main shaft 4 thereby revolving the disk 5 of the circuit interrupter, the speed of the 75 main shaft being less than that of the motor shaft incident to the step down gear system connecting the same.

The motor 27 is connected in parallel with the lighting circuit or located in any other 80 circuit and connected in the motor circuit is a controlling switch 34, shown in Fig. 4 and composed, in the present instance, of a copper brush 35 and a copper arm 36 pivoted at one end within a bracket 37 and having 85 the opposite end equipped with a yoke 38 carrying a carbon block 39 adapted, when the arm is swung in one direction, to engage the brush 35 and so close the motor circuit and when operated in the reverse direction 90 to disengage the copper brush and break the motor circuit. A leaf spring 40 has one end fixed to the bracket 37 and the opposite end working within a slot formed in the bottom wall of the block 39, such spring acting to hold the arm 36 normally in circuit 95 opening position.

Located in proximity to the switch 34 is an operating device therefor comprising a solenoid 41 having a core 42 therein connected with a horizontal stem 43 mounted for sliding movement within alining bearings 44 and provided with a laterally projecting finger 45 having the outer end thereof in engagement with the arm 36 105 carrying the carbon block 39 as clearly illustrated in Figs. 3 and 7. By means of this construction, it will be seen that when the solenoid is energized the core 41 therein will be actuated to slide the stem 43 whereby 110 the finger 45 will throw the arm 36 to engage the carbon block 39 with the copper brush 35 and so close the motor circuit.

Succeeding the closing of the switch 34 as just described the stem and core of the solenoid are latched against movement to normal position under the action of the leaf spring 40, such latching device, as shown in Figs. 2, 3, 7 and 8 comprising a finger 46 secured to the outer end of the stem 43 at 115 right angles thereto and provided with a right angularly arranged extension 43' of a length equal to the path of movement of the stem and lying parallel with the latter, and a trigger 47 pivoted adjacent to one end 120 upon a support 48 carried by the outer bearing of the stem 43, a contractile spring 49 having one end secured to the support 48 and the opposite end to the adjacent extremity of the trigger 47 and acting nor- 130

mally to throw the trigger in the path of movement of the extension on the finger 46. Thus, the trigger 47 will enter the path of movement of the extension 43' on the finger 46 succeeding the closing of the switch 34 thereby holding the stem against movement to normal position preventing the opening of the switch subsequent to the deenergization of the solenoid. This solenoid may be connected in multiple with the lighting circuit or connected in any other circuit and is preferably controlled by a manually operable switch.

In order that the switch 34 will be opened at a predetermined time so that the motor will be deenergized and the device thrown out of action, I employ a controlling device operable from the motor and connected thereto through the medium of a system of step down gearing so that after the expiration of a certain interval of time the latching device of the stem 43 will be released and the latter restored to normal position under the action of the spring 40. This controlling device, illustrated in Figs. 2, 3 and 5, comprises a disk 50 journaled upon a shaft 51 carried by a standard 52 uprising from the base 1. In the present instance, the step down gear system between the motor and the disk 50 comprises a worm 53 fixed to the main shaft 4 below the worm wheel thereon and meshing with a worm wheel 54 fast upon a shaft 55 journaled in horizontally alining bearings carried by the base. Keyed to the shaft 55 is a worm 56 meshing with a worm wheel 57 fast upon one end of a shaft 58 journaled in a bearing 59 and arranged at right angles to the shaft 55. Upon the oposite end of the shaft 58 is a pinion 60 meshing with a gear wheel 61 fast upon the inner face of the disk 50 on the shaft 51. Secured to the outer face of the disk 50 and extending radially thereof and spaced apart equal distances are arms 62 having the outer ends thereof beyond the periphery of the disk bent upon themselves as at 63 and adapted to engage the trigger 47 to actuate the latter against the action of the spring 49 whereby the switch 34 will be opened. In the present instance, I have shown three arms 62 on the outer surface of the disk 50 and with this construction the trigger will be actuated to released position five hours and twenty minutes after the closing of the motor circuit. However, the number of arms on the outer face of the controller disk may be varied so that the interval of time elapsing between the closing and opening of the main switch may be changed. In the present instance, the step down gear system between the motor and the controller disk is such that the controller disk makes one complete revolution every sixteen hours and should the disk be equipped with one arm only the

make and break device will operate continuously for sixteen hours. On the other hand, should the outer face of the disk be equipped with two arms 62 disposed diametrically opposite each other the main motor switch would be opened after the expiration of eight hours. When three arms are used the switch is opened after five hours and twenty minutes have elapsed, as before stated, while when four arms are employed the main switch is opened after the expiration of four hours, and so on, the time between the closing and opening of the switch being reduced inversely as the number of arms on the outer surface of the controller disk is increased.

From the foregoing description taken in connection with the accompanying drawings, the construction, mode of operation and manner of employing my invention will be readily apparent. It will be seen that I have provided a make and break device for electric circuits which is especially useful in conjunction with electric signs and analogous apparatus and whereby the banks of lamps or other ornaments may be alternately illuminated and extinguished and cut out of the circuit after the expiration of a certain period of time.

While I have herein shown and described one preferred form of my invention by way of illustration, I wish it to be understood that I do not limit or confine myself to the precise details of construction herein described and delineated, as modification and variation may be made within the scope of the claims without departing from the spirit of the invention.

I claim:

1. A make and break device for electric circuits comprising an interrupter, a motor for operating said interrupter, a circuit for said motor, a switch controlling said circuit, a stem connected to said switch, means for actuating said stem to close said switch, a latching device for maintaining said switch in closed position and comprising a finger secured to one end of said stem and having one extremity bent at right angles to itself and of a length equal to the path of movement of the stem, and a spring actuated trigger normally in engagement with the bent portion of said finger and adapted to enter the path of movement of the bent portion of the finger in the movement of the finger by the stem in the closing of the switch.

2. A make and break device for electric circuits comprising an interrupter, a motor for operating said interrupter, a circuit for said motor, a switch controlling said circuit, means for actuating said switch to closed position, a latching device for holding said switch in closed position, means for actuating said latching device to release the switch succeeding the operation of the circuit in-

terrupter after a predetermined time, said last-named means comprising a rotatable disk, fingers secured to said disk and radiating from the center thereof, and adapted 5 to actuate said latching device to release said switch, and means for actuating said disk.

In testimony whereof I affix my signature in presence of two witnesses.

JOHN T. BOYLE.

Witnesses:

GEORGE F. LONGAN,
GEORGE S. CARNES.
